UNITED STATES PATENT OFFICE.

GEORGE DYER, OF WALLACETON, VIRGINIA.

GASOLINE DRUM COVER.

Application filed April 19, 1920. Serial No. 374,978.

To all whom it may concern:

Be it known that I, GEORGE DYER, a citizen of the United States, residing at Wallaceton, in the county of Norfolk and State 5 of Virginia, have invented certain new and useful Improvements in Gasoline Drum Covers, of which the following is a specification.

This invention relates to new and useful 10 improvements in closures, and particularly to means whereby the closure may be locked upon a receptacle to prevent unauthorized use of the contents of the receptacle, and which closure prevents water from gaining 15 access to the receptacle.

An important object of the invention is 20 to provide the closure with locking means which may be manipulated from the outside of the closure only by the party who possesses a key to the lock.

Another important object of the invention 25 is to provide locking means for a closure which means are adjustable to adapt the closure to receptacles having various sized filling openings.

Another object of the invention is to provide a device which is strong, durable, inexpensive to manufacture and highly efficient in practice.

30 Other objects and advantages of the invention will become apparent during the course of the following description.

In the accompanying drawings forming 35 a part of the application and wherein like numerals are employed to designate like parts throughout the several views,

Figure 1 is a plan view of the invention applied to the under side of a closure.

Figure 2 is a section taken on the line 40 2-2 of Figure 1.

Figure 3 is a fragmentary transverse section through the device taken on the line 3-3 of Figure 2.

Referring to the drawings, wherein for 45 the purpose of illustration is shown the preferred embodiment of the invention, the numeral 1 designates a closure or cover which has its central point highest so as to drain off snow, rain and other matter not 50 intended to be placed thereon. Although I have particularly devised the invention for use in connection with gasoline drums, the upper portion of which is designated by the numeral 2 as clearly seen in Figure 55 2, it is obvious that the invention may be used as other closures. The drum in this

particular instance is illustrated as having its upper end equipped with an inwardly turned annular flange 3. However, it is to be appreciated that other mechanical expedients may be employed instead of the flange 3 such as recesses in the sides of the receptacle; therefore as it is only necessary to provide the receptacle with oppositely disposed shoulders, the flange may be referred 65 to as shoulders.

To the under side of the closure I secure a diametrically extending strap 4 by means of rivets or other suitable means, and it will be noted that opposite ends of the strap 70 terminate short of the edges of the closure. One end of the strap is formed into a pair of oppositely diverging fingers 6 the ends of which are adapted to project beyond one edge of the closure as clearly 75 shown. The ends of these fingers 6 are adapted to engage a portion of the under side of the flange 3, while the edge of the closure engages with the top of the flange.

The medial portion of the strap is provided with an opening 7 in which is pivoted one end of a movable locking element 8 by means of a suitable bolt or rivet 9. A second opening 10 is provided in the strap at the end thereof opposite to the fingers 6, 85 and a groove 11 communicates with both these openings and the central opening. As seen in Figure 2, this groove 11 receives the major portion of the locking element, while the free end thereof covers or closes the 90 opening 10. The closure is also provided with an opening 12 which is disposed directly over the opening 10 whereby a loop 13 secured to the locking element may project through the openings to have its free 95 end disposed above the closure. A string or twine is secured to the loop for a purpose which will presently appear, and it is to be understood that a padlock, not shown, may be associated with the loop to lock the 100 locking element in a locked position.

In order that the device may be adapted to receptacles having various sized openings, an arm 15 is adjustably associated with the free end of the locking element. The 105 innermost end of this arm is slotted as at 16 whereby bolts 17 carried by the locking element may extend therethrough while nuts 18 may be threaded upon the bolts to maintain the arm in any desired adjusted position. The free end of this arm projects beyond the edge of the closure to be engaged

with the under side of a portion of the in-turned flange 3 of the receptacle.

When it is desired to position the closure upon a receptacle, the locking element 8 is 5 permitted to swing downwardly of the closure, while the operator retains his hold upon the twine 14 so that the locking element may be positioned when it is so desired. The closure is then tilted in relation to the receptacle so that the free ends of the fingers 10 6 may be positioned to engage the under side of portions of the inturned flange 3. The closure is then swung so that the opposite side thereof from which the fingers project 15 comes into close proximity with the top of the receptacle so that the edges of the closure rest upon the upper surface of the flange 3. By means of the twine 14, the locking element may be swung upon its 20 pivot until the free end of the adjustable arm engages with the under side of an in-turned flange. At this time, the loop 13 will project through and above the opening 12 in the closure and the shackle of a padlock 25 may be passed through the loop and snapped in a locked position. Consequently, it will then be impossible for any unauthorized person to remove the closure.

The foregoing description and the drawing 30 has reference to the preferred or approved form of my invention. It is to be understood however, that I may make such

changes in construction and combination of parts, materials, dimensions, etc., as may prove expedient and fall within the scope of 35 the appended claim.

Having thus fully described my invention what I claim as new and desire to secure by Letters Patent is:—

The combination with a receptacle, of a 40 closure therefor, a strap secured to the under side of the closure and extending across the same and having one end provided with diverging fingers adapted for engagement with one side of said receptacle, said strap 45 and closure having aligned openings near the opposite end thereof, a locking arm pivoted to said strap intermediate its ends thereof and adapted to be received within a slot in said strap, a locking arm adjustably 50 connected to said pivoted arm, and adapted to engage the opposite side of said receptacle, a loop secured to said pivoted arm and said locking arm, and adapted to be projected through said aligned openings when the 55 arm is in a locked position, and means for maintaining said locking element in a locked position.

In testimony whereof I affix my signature in presence of two witnesses.

GEO. DYER.
